UNITED STATES PATENT OFFICE.

THOMAS IRVING POTTER, OF PORTLAND, OREGON, ASSIGNOR TO COIN MACHINE MANUFACTURING COMPANY, OF PORTLAND, OREGON, A CORPORATION OF OREGON.

MECHANISM FOR CONTROLLING THE ENTRANCE TO EXHIBITION-GROUNDS.

1,179,754.

Specification of Letters Patent.

Patented Apr. 18, 1916.

Application filed May 6, 1914. Serial No. 836,832.

To all whom it may concern:

Be it known that I, THOMAS IRVING POTTER, a citizen of the United States, residing at Portland, in the county of Multnomah and State of Oregon, have invented certain new and useful Improvements in Mechanism for Controlling the Entrance to Exhibition-Grounds; and I do hereby declare the following to be a full, clear, and exact description of the same, reference being had to the accompanying drawings, forming part of this specification, and to the figures and letters of reference marked thereon.

The present invention relates to mechanism for regulating and controlling the entrance and registration of persons to exhibition grounds, buildings, etc., where large numbers of persons must be passed in a short period of time and an accurate record made of the number and the proper entrance fee collected from each.

The object of the invention is to provide a mechanical arrangement of a series of entrances which will permit of a maximum economy of space measured at right angles to the line of entrance and which will prevent succeeding persons from interfering with each other at the point where the entrance fee is paid and registration accomplished.

A further object of the invention is to provide a mechanical arrangement whereby adults and minors or children may be passed through and registered in separate entrances, without danger of the children and their adult guardians or parents becoming separated or lost from each other.

A further object of the invention is to provide an arrangement of the register controlling device which is in the form of a turnstile, in such wise that but one person can enter and pass through the same at one time, the following or succeeding person being barred by the register controlling mechanism itself, until such time as the registration of the first person entering shall have been completed.

The invention consists in certain novel details of construction and combinations and arrangements of parts all as will be herein-after described and pointed out particularly in the appended claims.

The accompanying drawing is a diagrammatic plan view of a portion of an entrance

mechanism embodying the present improvements.

In said drawing, the figure 1 indicates a turnstile, there being a series of such turnstiles arranged in a row relatively close together and each embodies a series, preferably 4, substantially fan-shaped or segmental arms with their apices toward the axis of the turnstile, thus providing recesses which will accommodate the body of one person in passing through the entrance bridged by the arms of the turnstile. Between each of said recesses the segmental or fan-shaped outer ends of the arms form broad barriers which will bar the entrance of a succeeding person, while the stile is being turned during the passage of the preceding person past the same.

The passageways and openings leading to and from the turnstiles are formed by guard rails arranged at a proper height to direct the persons entering through the turnstiles. Generally stated, the arrangement of rails is such that the passageways leading to and from each turnstile are out of alinement with each other, although extending in a generally parallel direction and the openings from said passageways to and from the turnstile are at substantially right angles to each other, whereby a person entering through the entrance passageway moves at right angles from the passageway into the turnstile and over into alinement with the exit opening and passageway in a continuous onward movement, this arrangement being particularly advantageous in that by the change of direction of movement, crowding and interference of persons succeeding each other in close order is largely prevented at the point where the turnstiles are located, whereby two important objects are attained.

The first is the prevention of more than a single person crowding into the same turnstile recess, and the second is the convenience with which a person approaching the turnstile for entrance may deal with the gate keeper who is located immediately beyond the end of the entrance passageway and is directly faced by the person entering through said passageway.

Referring to the drawing, it will be seen that each entrance passageway, such as 7, 8 and 9, is defined by guard rails 5 and 5^a, and each exit passageway such as 7^a, 8^a and

9^a is defined by guard rails 16 and 17, the two passageways of each turnstile are offset or located out of line with each other, and the turnstiles are located in the offset, so 5 that the entrance and exit openings leading from the entrance passageways to the turnstile and from the turnstile to the exit passageways are at substantially right angles to each other. At the inner end of the entrance 10 passageways there are located tables or counters 2, preferably forming guards which extend from the guard rails 5 to the guard rails 17, and in or on each table or counter there is an opening or receptacle 15 3 for the reception of the entrance fee or ticket. Connecting the guard rails forming the opposite sides of the passages from the tables or counters 2, there are curved guard rail extensions 4 passing partly over the turnstiles, so as to effectually prevent the persons entering through the turnstile from passing around or rotating the turnstiles in the wrong direction.

Guard rails 10, 11 and 13 and 14 are located in front of the turnstiles and form in effect the front barriers between the entrance passageways 7, 8 and 9, and to make provision whereby adults and children or minors may be passed through the entrance 25 and registered by different turnstiles without moving out of sight of or being separated from each other, and at the same time provide for a greater number of entrances for adults than for children, an entrance for children or minors is arranged 30 between two entrances for adults.

As shown in the drawings, two entrances 7' and 9' are provided for each set of three turnstiles, the guard rails 10 and 11 being 40 located within the line of the guard rails 13 and 14 and a supplemental guard rail 12 being provided to define the entrances 7' and 9' and form a passageway 8' leading from the main entrances toward the intermediate entrance passageway 8, for children 45 or minors. With this arrangement, children and their guardians entering through either entrance 7' or 9' will separate, the children turning off at right angles through the passageway 8' and entering through the entrance passageway 8, while the adults will 50 enter through passageways 7 or 9. The guard rails are low enough to permit children to remain in sight of and close by their parents or guardians. The arrangement permits the turnstiles to be located close together, or with only sufficient space between them for the movement of the arms, and inasmuch as the entrance and exit passageways are all offset in the same direction, a 55 very considerable economy of space is effected.

In use, all persons entering through the entrance passageways approach the gate 60 keepers or attendants located behind the

tables 2 in a forward direction with their backs to the persons following them. After the entrance fee transaction during which no one else can crowd in beside them, they move off laterally into and through the turnstile and are in position to pass out through the exit passageways. The turnstiles being located in the offsets between the passageways will register the entrance of each person by a quarter turn and the arms which precede and follow the one barring the entrance do not obstruct either the entrance or exit passageways or opening, even though there should be considerable lost motion between the successive movements of the turnstiles.

Having thus described my invention what I claim as new and desire to secure by Letters Patent of the United States, is:

1. In an entrance mechanism for exhibition grounds, etc., the combination with a series of turnstiles arranged in a line, and guard rails forming passageways leading to and away from the turnstiles, said passageways being located out of alinement 90 with each other and having entrance and exit opening to and from the turnstiles at substantially right angles to each other, whereby crowding and interference with each other by persons passing through the turnstiles is prevented and a continuous onward movement of the persons permitted and an attendant's counter located across the inner end of the entrance passageway.

2. In an entrance mechanism for exhibition grounds, etc., the combination with a series of turnstiles and guard rails forming entrance and exit passageways therefor, said passageways being arranged in substantial parallelism, but the entrance and exit passageways of each turnstile being offset 105 with relation to each other and having their entrance and exit openings adjacent the turnstiles at substantially right angles to each other, and an attendant's 110 counter located across the inner end of the entrance passageway and directly in front of the person entering through said passageway.

3. In an entrance mechanism for exhibition grounds, etc., the combination with a series of turnstiles arranged in sets of three, the center stile of each set being provided for minors and the end stiles of each set for adults, of inner and outer rails forming entrance openings for said turnstiles, and a guard rail intermediate and in alinement 120 with the outer guard rails of the end turnstiles to prevent direct entrance to said center entrance.

4. In an entrance mechanism for exhibition grounds, etc., the combination with a series of turnstiles arranged in sets of three, the end turnstiles being provided for adults and the center turnstile for minors, of guard 125

rails forming exit and entrance passageways for said turnstiles, the rails forming the extreme sides of the end turnstile entrances extending beyond the other rails, and a side guard rails of the end entrances whereby 10 a passageway for minors only is formed from the end entrances to the center entrance.

5 guard rail located in front of the center entrance passage to prevent direct entry to said passage, said last mentioned rail being spaced from the center entrance and in line with the outer extremities of the extreme
